UNITED STATES PATENT OFFICE.

HOMER P. CHANDLER, OF MANSFIELD, OHIO, ASSIGNOR TO THE OHIO BRASS COMPANY, OF MANSFIELD, OHIO, A CORPORATION OF NEW JERSEY.

CONDUCTOR SUPPORT.

Application filed November 29, 1922. Serial No. 603,947.

To all whom it may concern:

Be it known that I, HOMER P. CHANDLER, a citizen of the United States of America, residing at Mansfield, in the county of Rich-
5 land and State of Ohio, have invented cer-
tain new and useful Improvements in Con-
ductor Supports, of which the following is
a specification.

My invention relates to supports for elec-
10 tric conductors and particularly that class
of supports used for suspending a trolley
wire or conductor from an overhead hanger.

The object of my invention is to produce a
15 device which will be simple, efficient, easy of
installation and operation.

Another object of my invention is to pro-
duce a device of the character stated in
which the jaws can be moved to a closed po-
sition as when the clamp is in gripping en-
20 gagement with a trolley conductor and also
in which the parts can be moved to an open
position and maintained in such position
without the use of auxiliary means.

It has been a general practice in the past to
25 use clamps having means for bringing the
jaws into secure gripping engagement with
the conductor and maintain them in this
position, but such clamps have not had means
30 for moving the jaws to an open position
out of engagement with the conductor other
than by means of the hands. In some types
of clamps in which the jaws are loosely sus-
35 pended the center of gravity has been such
that under certain conditions the jaws would
hang open by gravity when not in clamping
engagement with the conductor, but such
clamps have not had a positive means for
40 moving the jaws to and maintaining them
in an open position.

My invention resides in the new and novel
construction, combination and arrangement
of the various parts hereinafter fully de-
scribed and shown in the drawings.

In the accompanying drawing:

45 Fig. 1 is a side view in elevation of a
clamp embodying my invention.

Fig. 2 is an end view in elevation of Fig. 1.

Fig. 3 is a sectional view of Fig. 1 on the
line 3—3 and shows the device as secured
50 to a hanger.

Fig. 4 is a longitudinal sectional view on
the line 4—4 of Fig. 2.

Fig. 5 is a sectional view corresponding
with that of Fig. 3, but in which the jaws
are shown maintained in an open position. 55

Fig. 6 is a sectional view of Fig. 3 on the
line 6—6.

I have shown the device attached to a
hanger only in Fig. 3, but it will be readily
understood that the hanger is applicable to 60
all the other figures in a similar manner.

In my preferred construction embodying
my invention I employ a supporting member
1 provided with a flange 2 and a threaded
socket 3 to receive a threaded hanger stud H. 65
To the lower end of the supporting member
1 is a depending lug 4 provided with a pas-
sage for a pin 5. Pivotaly associated with
the supporting member 1 are a pair of jaws
6—6 having at their lower end lips 7 to en-
70 gage a trolley conductor C. At the upper
end of each jaw is a pair of lugs 8' and 8''.
The lugs 8' and 8'' are each provided with
a passage to receive the pin 5 and when as-
sembled in combination with the support 75
member 1 they pivot freely about the pin 5.
Exterior of and near the top of each jaw is
a shoulder 9 and also a hook shaped lip 10
forming a channel 11. From the above de-
scription it will be noted that the jaws are 80
duplicates and therefore, interchangeable.

Rotatably mounted on the supporting
member 1 is an operating member 12 having
a threaded engagement 13 with the support-
ing member 1 whereby the operating mem-
ber moves toward or away from the con-
ductor when rotated. 85

The lower part of the operating member
is formed with an enlarged annular recess
14 and an annular channel 15 due to the hook
shaped flange 16 at the lower end of the
operating member. The lower end of the op-
erating member and the upper end of each
clamp interlock through the member 10
projecting into the channel 15 and the hook
shaped member 16 projecting into the chan-
nel 11. The arrangement is such that the
member 16 will engage either the member
9 or the member 10, depending whether the
operating member is moved toward or away 100

- from the conductor when rotated. The upper end of the operating member 12 is provided with an annular lip 17 adapted to be turned inwardly after assembling the 5 various parts so that it will engage the flange 2 on the support member and thereby limit the movement of the operating member in one direction and prevent the disassembly of the parts.
- 10 In assembling my device I first position the operating member upon the supporting member until the shoulder 18 engages with the flange 2. I then position the jaws upon the supporting member by means of the pin 15 5 and open the jaws as far as possible about the pin 5 in which position I am then able to screw the operating member toward the jaws until the members 10 will interlock with the operating member as previously described. The annular flange 17 is then rolled inwardly until it will interlap with the flange 2 thereby limiting the upward movement of the operating member so that the lower edge A of the operating member (see 20 Fig. 5) will still engage with the pin 5 thereby preventing the displacement of the pin 5 and the disassembly of the parts forming the clamp. The engagement of the flange 17 with the flange 2 also limits the extent 25 to which the jaws can be opened.
- In installing my device upon a hanger and conductor I first screw the clamp into position upon the hanger stud H and bring the jaws 6 into alignment with the trolley wire. 30 If the lips 7 are not opened sufficiently to receive the conductor by rotating the operating member 12 in one direction, the jaws will be moved to an open position sufficient to receive the trolley wire. The operator then 35 positions the conductor between the lips 7 and by rotating the operating member in the opposite direction from that required to open the jaws, the jaws will be closed and the lips brought into engagement with the conductor 40 thereby holding the conductor in position. By applying a wrench to the faces 19 of the operating member the jaws can be brought 45 into further and more secure engagement with the conductor.
- 50 It will be noted that in Fig. 3 the member 16 engages with the member 9 when the parts are forced into and held in engagement with the trolley conductor, and that in Fig. 5 the member 16 engages with the member 10 when the parts are opened up and held in an 55 open position.
- There are numerous modifications which can be made from the construction herein described and shown and which will fall within 60 the scope of my invention and, therefore, I do not wish to be limited other than by my claims.
- I claim—
1. A conductor clamp comprising in combination a pair of jaws to grip a conductor, means to secure the jaws to a hanger and means to move the jaws either into or out of engagement with the conductor at will. 65
  2. The combination with a conductor clamp comprising a pair of jaws to grip a conductor and means to secure the jaws to a hanger, of means to open the jaws when moved in one direction and to close the jaws when moved in the other direction. 70
  3. The combination with a conductor clamp comprising a pair of jaws to grip a conductor and means to secure the jaws to a hanger, of means interlocked with the jaws to open the jaws when moved in one direction and to close the jaws when moved in the other direction. 75
  4. The combination with a conductor clamp comprising a pair of jaws to grip a conductor and means to secure the jaws to a hanger, of means interlocked with the jaws and support to open the jaws when moved in one direction and to close the jaws when moved in the other direction. 80
  5. The combination with a conductor clamp comprising a pair of jaws to grip a conductor and means to secure the jaws to a hanger, of means interlocked with the jaws and support for relative rotation thereto to open the jaws when moved in one direction and to close the jaws when moved in the other direction. 85
  6. The combination with a conductor clamp comprising a pair of jaws to grip a conductor and means to secure the jaws to a hanger, of means movable in a transverse direction to the axis of the conductor to open the jaws when moved in one direction and to close the jaws when moved in the other direction. 90
  7. The combination with a conductor clamp comprising a pair of jaws to grip a conductor and means to secure the jaws to a hanger, of means movable towards the conductor to move the jaws into engagement with the conductor and movable away from the conductor to move the jaws out of engagement with the conductor. 95
  8. A conductor clamp comprising in combination a pair of jaws pivoted together to grip a conductor, a means to secure the jaws to a hanger and means to move the jaws either into or out of engagement with the conductor about the pivotal point. 100
  9. A conductor clamp comprising in combination a pair of jaws mounted on a support member in pivotal relation thereto, a support member to secure the jaws to a hanger and means to move the jaws either into or out of engagement with the conductor. 105
  10. A conductor clamp comprising in combination a pair of jaws, supporting means to secure the jaws to a hanger, and operat- 110

ing means threadedly mounted on the supporting means to engage means on the jaws to move them into engagement with the conductor when rotated in one direction and to engage means on the jaw to move the jaws out of engagement with the conductor when rotated in the opposite direction.

11. A conductor clamp comprising in combination a pair of jaws, supporting means to secure the jaws to a hanger, and operating means mounted on the supporting means to move the jaws into engagement with the conductor when rotated in one direction and to move the jaws out of engagement with the conductor when rotated in the opposite direction.

12. A conductor clamp comprising in combination a pair of jaws, supporting means to secure the jaws to a hanger, operating means threadably mounted on the supporting means and interlocked with the jaws to cause the jaws to open when the operating means is rotated in one direction and to close when rotated in the opposite direction.

13. A conductor clamp comprising in combination a pair of jaws, supporting means to secure the jaws to a hanger, operating means rotatably mounted on the supporting means and movable transversely of the axis of the conductor when rotated and means on the operating means engaging means on the jaws to move the jaws when the operating means is moved in either transverse direction to open or close the jaws.

14. A conductor clamp comprising in combination a pair of jaws, supporting means to secure the jaws to a hanger, operating means rotatably mounted on the supporting means and movable transversely of the axis of the conductor when rotated, means on the operating means engaging means on the jaws to move the jaws when the operating means is moved in either transverse direction to open or close the jaws and means to move the operating means in one transverse direction when the operating means is rotated in one direction and to move the operating means in the other transverse direction when the operating means is rotated in the other direction.

15. A conductor clamp comprising in combination a pair of jaws, means which the jaws pivotally engage to secure the jaws to a hanger, operating means to engage the jaws at a point below the pivotal axis to move the jaws into engagement with a conductor and to engage means on the jaws above the pivotal axis to move the jaws away from the conductor.

16. A conductor clamp comprising in combination a pair of jaws to grip a conductor, means to secure the jaws to a hanger, means to move the jaws either into or out of engagement with the conductor at will

and means to limit the opening of the jaws when moved out of engagement with the conductor.

17. A conductor clamp comprising in combination a pair of jaws to grip a conductor, means to secure the jaws to a hanger, means to move the jaws either into or out of engagement with the conductor at will and means interposed between the said means to limit the opening of the jaws when moved out of engagement with the conductor.

18. A conductor clamp comprising in combination a support member having means to engage a hanger, a pair of jaws pivotally mounted thereon to grip a conductor, an operating member on the support member to move transversely of the conductor axis when rotated, means on the operating member forming an annular channel in a plane parallel with the axis of the conductor, means on each jaw extending into the channel to move the jaws to an open position when the operating member is moved in one direction.

19. A conductor clamp comprising in combination a support, a pair of jaws cooperating therewith to move into and out of engagement with a conductor, an operating member to move the jaws into engagement with the conductor and means to hold the jaws open when not in engagement with the conductor.

20. A conductor clamp comprising in combination a support, a pair of jaws cooperating with the support to open and close with respect to a conductor, means on each jaw forming a channel, an operating member, means on the operating member positioned within the channel to either open or close the jaws as the operating member is moved in one direction or the other direction.

21. A conductor clamp comprising in combination a pair of jaws to engage a conductor, supporting means to secure the jaws to a hanger, operating means engaging the jaws to simultaneously move them when the operating means is moved either into or out of engagement with the conductor when the operating means is moved in one or the other direction.

22. A conductor clamp comprising in combination a pair of jaws to engage a conductor each jaw engaging operating means to move it either towards or away from the conductor and means to secure the operating means and jaws to a hanger.

23. A conductor clamp comprising in combination a pair of jaws to grip a conductor, common means to move the jaws simultaneously towards the conductor when moved in one direction and to move the jaws simultaneously away from each other when moved in the other direction and

means to secure the above elements to a hanger.

24. A conductor clamp comprising in combination a pair of jaws secured to a hanger and arranged to grip a conductor and operating means having a rotative movement and a simultaneous movement towards or away from the conductor depending upon the direction of rotation and arranged to move the jaws into or out of en-

gagement with the conductor simultaneously with the rotation of the operating member in one direction or the other.

25. A conductor clamp comprising in combination means to grip a conductor, means to secure the gripping means to a support and means to open the gripping means to receive the conductor. 15

In testimony whereof I affix my signature.
HOMER P. CHANDLER.
